UNITED STATES PATENT OFFICE

JAMES S. MOSS, OF INDIANAPOLIS, INDIANA

COMBINED CURTAIN-ROD AND WINDOW-SHADE MOUNTING

Application filed February 26, 1929. Serial No. 342,744.

This invention relates to a combined curtain rod and window shade mounting, and has for an important object thereof the provision of a device of this character which may 5 be very readily attached to the window frame without in any manner marring the same and without the use of tools other than the ordinary screw driver.

A further object of the invention is to provide a device of this character which is adjustable so that it may be employed with window frames, the frame elements of which are of different widths and which is likewise adjustable to permit use thereof with curtain 15 shades and curtain rods of varying lengths.

A still further object of the invention is to produce a device of this character which may be very readily and cheaply manufactured.

These and other objects I attain by the construction shown in the accompanying drawings, wherein for the purpose of illustration is shown a preferred embodiment of my invention and wherein:

Figure 1 is a front elevation of a combined 25 curtain rod and shade bracket constructed in accordance with my invention;

Figure 2 is a plan view thereof;

Figure 3 is an enlarged sectional view on the line 3—3 of Figure 2;

Figure 4 is a sectional view on the line 4—4 of Figure 3;

Figure 5 is a section on the line 5—5 of Figure 3.

Referring now more particularly to the 35 drawings, the combined bracket and shade mounting constructed in accordance with my invention comprises a base formed from a single strip of metal, indicated generally at 10. The ends of this strip are bent to form 40 flanges 11 lying at the same side of the strip and the intermediate portion of the flange adjacent one end is looped upwardly, as indicated at 12, to form a substantially U-shaped loop, adjacent faces of the arms 13 of which 45 are spaced from one another, and by the inherent resiliency of the material employed tend to remain in such spaced relation. Through these arms, a securing element 14 is directed for drawing the arms toward one 50 another, so that the flanges 11 may be caused

to approach one another and clamp upon opposite side faces of the frame element E of a window frame. Between said loop and its opposite end, the strip has extending inwardly from opposite side edges thereof slits 15, 55 the slits at the same side of the strip being spaced from one another and the metal flap 16 formed between these slits being reverted upon the outer face of the strip in spaced relation thereto to form channels 17 receiving the 60 side edges of plates 18 and 19. The plates 18 and 19 mount respectively a shade roller bracket 20 and a curtain rod mounting 21. At the present time, I have illustrated the 65 curtain rod mounting as adapted for coaction with the tubular type of curtain rod but it will, of course, be understood that not only may the type of mounting employed be varied but this may be accomplished without in any 70 way altering the structure of the base element 10 employed.

It will also be understood that the shade roller brackets 20 will be made in pairs.

I have at present illustrated the shade roller bracket as constructed integrally with 75 its plate and the curtain rod fixture 21 as attached to its plate. Obviously, these structures might be reversed or both of these structures either made integral with, or detachable from each other as is desired. Means are provided for securing the plates 18 and 19 in 80 desired adjusted position, these means being at present illustrated as screws 22 extending through one of the reverted flaps 16 and engaging the plates. It will also be obvious that 85 this arrangement is capable of considerable modification.

In installing fixtures of this character, it is merely necessary that the screw 14 be loosened to enable the flanges to be engaged with opposite edges of the frame element E while the inner face of the plate abuts the outer face of this element. The screw 14 is then tightened to draw these flanges firmly against opposite edges of this element and thus clamp the base 90 in position thereon. The plates 18 and 19 may then be adjusted to their proper positions for supporting the shade and curtain.

Since, as above pointed out, the structure is 100 capable of a certain range of change and

modification without materially departing from the spirit of the invention, I do not limit myself thereto except as hereinafter claimed.

I claim:—

- 5 A shade bracket of the type described comprising an elongated resilient strip having flanges at the opposite ends thereof and an intermediate U-shaped loop formed between the flanges, a threaded bolt mounted in the loop portion of said strip and adapted to pull the flanges toward each other whereby to clamp the strip upon a window frame, a pair of guide members integrally formed with said strip and comprising an upper and a lower elongated portion bent inwardly from the upper and lower edge portions of said strip, a shade roller bracket adapted to be mounted in said guide, and a curtain bracket adapted to be mounted in said guide.
- 10
- 15
- 20 In testimony whereof I hereunto affix my signature.

JAMES S. MOSS.
